GRINDING APPARATUS

Anton J. Brunner, Congress Park, and August Wennerberg, Chicago, Ill., assignors to Western Electric Company, Incorporated, New York, N. Y., a corporation of New York

Application October 10, 1945, Serial No. 621,581

6 Claims. (Cl. 51—110)

1

This invention relates to grinding apparatus and more particularly to an apparatus for surface grinding flexible strip material to predetermined thickness.

The invention is particularly useful in grinding flat insulator cores or cards to be subsequently shaped and wound with wire to provide resistances for use in potentiometers of the type used in radar equipment. Such cards may comprise flat relatively thin strips of phenol fibre or rubber, some types of which are from 30" to 60" in length. In order to wind such resistance cards with accuracy, it is very necessary that the blanks from which the cards are shaped be ground to a high degree of precision and a required uniform thickness throughout their length.

An object of the present invention is the provision of a practicable and efficient apparatus for grinding flexible strip material with precision and a required uniform thickness.

In accordance with one embodiment of the invention, which is illustrated herein as applied to the grinding of insulator card blanks, referred to above, to predetermined thicknesses, a grinding apparatus is provided which includes a cup-shaped rotatable grinding wheel having an annular abrasive face for engaging the face of a card blank to be ground, which is being fed across a backing plate in a direction perpendicular to the axis of the wheel, rotatable in a fixed position, by cooperating pairs of feed rollers, one set at each side of the wheel, the pair of rollers at the exit end of the apparatus being in a different horizontal plane than the rollers at the entrance end so that only an arc or portion of the annular abrasive face of the wheel adjacent the entrance end is effective to grind the card blank. The rollers of each pair are positively driven, one roller being operatively yieldably mounted relative thereto. For the purpose of feeding the card blank under desired longitudinal tension during its grinding, the rollers at the exit end have a slightly larger periphery than the rollers at the entrance end. Guide means for the card blank are provided for directing it between the feed rollers at the entrance end and adjacent each side of the portion of the annular abrasive face of the wheel which engages the card blank for guiding the blank between the abrasive face and the backing plate and thence in an inclined plane to and between the feed rollers at the exit end. The feed rollers, guide means and backing plate are mounted for unitary movement upon an adjustable frame whereby, as the annular abrasive face of the grinding wheel wears and is dressed, these elements may be moved accordingly.

Other objects and advantages of this invention will more fully appear from the following detailed description, taken in conjunction with the accompanying drawings, in which

2

Fig. 1 is a fragmentary front elevational view of a grinding apparatus embodying the features of this invention;

Fig. 2 is a fragmentary vertical section, partly in elevation, taken on the lines 2—2 of Fig. 1;

Fig. 3 is an enlarged fragmentary vertical section taken on the lines 3—3 of Fig. 2;

Fig. 4 is a fragmentary plan view, partly in section, taken on the lines 4—4 of Fig. 3; and

Fig. 5 is an enlarged detail plan section taken on the lines 5—5 of Fig. 1.

Referring to the drawings and particularly to Figs. 1 and 2, the numeral 10 indicates, in general, a fixed frame comprising two spaced standards 11 supported at their lower ends on a suitable base (not shown). Fixed to and interconnecting the standards 11 are spaced horizontal cross members 12, 13 and 14. Carried upon the cross member 12 intermediate the standards 11 is an electric motor 17 having its driving shaft 18 (Figs. 2 and 3) vertically disposed and having fixed thereto at its lower end an inverted cup-shaped grinding wheel 19 made of a suitable abrasive material, its lower annular face 20 engaging the upper face of a strip of material or, in the present instance, a card blank 21 (Fig. 3) which is to be ground to a predetermined thickness.

Arranged between the cross members 12 and 13 is an irregular shaped vertically adjustable hollow frame 24 extending perpendicular to the axis of rotation of the grinding wheel 19 and having three compartments 25, 26 and 27 open at their tops. Attached to a central bearing portion 28 of the frame 24 in axial alignment with the grinding wheel 19 and depending therefrom is a hollow guide post 31, circular in cross-section, and slidably fitted in the cross members 13 and 14. Secured to the upper annular face of the bearing portion 28 is a cap plate 32, the upper end face of the post 31 abutting a lower recessed face of the plate. Fixed to and depending from the bearing portion 28 at its right side (Figs. 1, 2 and 3) is a rod 33 having its lower end screw-threaded (Fig. 2) and slidably fitted in the cross member 13 and in an irregular shaped hollow standard 34 carried upon the cross member 14. Rotatable upon the screw-threaded portion of the rod 33 is a circular nut 35 having formed on its periphery worm gear teeth which mesh with a worm 36 fixed to a shaft 39 journalled in the standard 34, the nut being prevented from moving upwardly or downwardly upon the rod 33 during its rotation since it is confined by abutting faces of the cross member 13 and the standard 34. Fixed to the outer end of the shaft 39 (Fig. 1) is a hand wheel 40. Also fixed to and depending from the bearing portion 28 at its left side (Figs. 1 and 3) is a rod 41 slidably fitted in the cross member 13 and having screw-threaded onto its lower end below the cross member 13 is a pair

of stop nuts 42. It will be apparent, for a purpose to be referred to hereinafter, that upon rotating the hand wheel 40 in one direction or the other, the frame 24 may be adjusted upwardly or downwardly relative to the grinding wheel 19. Upon the frame 24 being properly adjusted, the stop nuts 42 are rotated on the rod 41 into operative stop relation with the bottom face of the cross member 13, thus preventing accidental upward movement of the frame after its adjustment. In order to lock the frame 24 from accidental movement either upwardly or downwardly after its adjustment, the guide post 31 is clamped to the cross member 13 by a pair of opposed shoes 45 and 46 (Fig. 5) longitudinally slideable in the cross member and formed with arcuate faces 47 engaging the peripheral face of the post 31. Fixed to the shoe 45 is a rod 48, which extends freely through the shoe 46 and is screw-threaded at its outer end, upon which end is screw-threaded a handle 49. By rotating the handle 49 in one direction, the shoes 45 and 46 are drawn into clamping engagement with the post 31, an opposite direction of rotation of the handle releasing the shoes.

At the entrance or the left end of the apparatus (Fig. 3) within the compartment 25 of the adjustable frame 24 is a pair of feed rollers 50 and 51 and at the exit or right end, within the compartment 27, is a pair of rollers 52 and 53. The latter rollers are slightly larger in diameter than the rollers 50 and 51 and consequently have a greater peripheral surface speed than the rollers 50 and 51 since, as will be described presently, both pairs of rollers are driven at identical speeds. Thus the rollers 52 and 53, when the strip or card 21 is gripped by both sets of rollers, serve to maintain the strip under tension. Since the two sets of rollers are carried on the frame 24 within the compartments 25 and 27 by similar means, although in different horizontal planes for a purpose to be described hereinafter, the arrangement for supporting the rollers 50 and 51 at the entrance end of the apparatus will be described, it being understood that the following description also applies to the rollers 52 and 53.

Secured to opposite side walls of the compartment 25 within openings therein are bearing blocks 54, in which are journaled in fixed bearing portions thereof opposite reduced ends of the roller 51. Carried in openings formed in the blocks 54 are vertically adjustable bearing blocks 57, in which are journaled opposite reduced ends of the roller 50, the roller being adjustably yieldably urged toward the roller 51 by compression springs 58 bearing at opposite ends upon the blocks 57 and adjusting screws 59 threaded into the blocks 54. The strip or card 21 is advanced through the apparatus by the cooperating sets of feed rollers 50 and 51 and 52 and 53 at a predetermined constant rate such that the velocity and abrasive action of the grinding wheel 19 upon the card 21 does not retard the advance of the card. To insure a positive advancing action of both rollers of each pair upon the card 21, each roller, as shown in Fig. 4, has fixed thereto a gear 60, the gear 60 of each pair of rollers being similar and in mesh and upon the rollers 51 and 53 being rotated in a clockwise direction, it will be apparent that the rollers 50 and 52 will be rotated counterclockwise and at their adjacent peripheral portions a similar advancing action on the card 21, as indicated by the arrows upon the rollers (Fig. 3) will be affected.

The rollers 51 and 53 are driven simultaneously and at the same velocity by means of a sprocket

chain 61 (Figs. 1 and 2) which meshes with similar sprocket wheels 64 fixed to the rollers 51 and 53, the chain passing over idler sprocket wheels 65 journaled on the frame 24 and thence around a sprocket wheel 66 secured to a shaft 67 journaled on a bearing bracket 68 fixed to the post 31. Secured to the shaft 67 is a worm wheel 71 meshing with a worm wheel 72 fixed to a shaft 73, which is also journaled on the bracket 68. To the shaft 73 is secured a sprocket wheel 74 around which extends a sprocket chain 75, shown fragmentarily, which may be driven from a sprocket wheel attached to the output shaft of a speed reducing mechanism coupled to an electric motor, such mechanism and motor being preferably mounted on the fixed frame 10. The electric motor and speed reducing mechanism, since they form no part of this invention are not believed necessary to a complete understanding thereof, have been omitted from the drawings for the sake of simplicity. During any necessary adjustment of the frame 24 with the attached post 31 and other parts upwardly or downwardly by means of the hand wheel 40 it will be understood that the sprocket wheel 74 and chain 75, which move with the post 31, may rock about the fixed axis of the sprocket wheel on the output shaft of the speed reducing mechanism (not shown), sufficient play being arranged in the sprocket chain 75 to permit this movement.

Referring particularly to Figs. 3 and 4, suitable strip or card guiding means comprising three separate units are indicated in general at 76, 77 and 78, which are supported on the frame 24. Each of the guide units 76, 77 and 78 comprise spaced and united upper and lower plates, between which the strip or card 21 may freely pass in its advance through the apparatus. The guide unit 76 at the entrance end of the apparatus, referring to the left side of Fig. 3, extends through an opening in the wall of the compartment 25 and to a point intermediate and adjacent the feed rollers 50 and 51, the lower plate extending appreciably to the left of the frame 24 to provide a table or apron upon which the strip or card 21 is first placed and then advanced inwardly toward the feed rollers 50 and 51, which grip and advance it to the feed rollers 52 and 53. Between the feed rollers 50 and 51 and the grinding wheel 19 is arranged the guide unit 77 having the upper face of the lower plate thereof in the plane of the upper face of an irregular arcuate shaped member 79 mounted upon and secured to the cap plate 32, which forms a backing plate for supporting the advancing strip or card 21 during the grinding thereof by the opposed annular face 20 of the grinding wheel 19. The guide unit 77 extends from a point arranged in the plane of the guide unit 76 and adjacent the feed rollers 50 and 51, through a slot in the wall between the compartments 25 and 26 and terminates in suitable spaced relation with the periphery of the rotating grinding wheel 19, the lower face of the upper plate being substantially in the plane of the lowermost point of the annular grinding face 20 of the wheel 19. Inclined from a point intermediate and adjacent the feed rollers 52 and 53, which are arranged slightly below the feed rollers 50 and 52, and extending to a point adjacent the inner periphery of the grinding wheel 19 and substantially in the plane of the guiding unit 78 is the guiding unit 78. At its left end (Fig. 3), the lower plate of the unit 78 rests on an irregular shaped shouldered portion 80 of the backing plate 79 and in the plane of the upper face thereof, which is slightly inclined to meet it.

The upper plate of the unit 78 lies substantially in the plane of the upper plate of the unit 77 and terminates adjacent the inner periphery of the grinding wheel 19. In offset relation adjacent the right side of the grinding wheel 19 (Fig. 3), the upper and lower plates of the unit 78 are split and carried between spaced adjacent ends of the plates and supported thereon are brushes 83 and 84 of felt or other suitable material arranged in wiping relation with opposite longitudinal faces of the advancing strip or card 21, which are effective to prevent ground particles carried by the card from getting between the feed rollers 52 and 53. Particles brushed from the faces of the card drop into the bottom of the compartment 26 through spaces 85 provided between guide plates 86, which space the upper and lower guide plates of the unit 78. The unit 78 extends through a slot in the wall between the compartments 26 and 27; the slot above the unit 20 being sealed by plates 87.

The upper surface of the strip or card 21, as it nears the annular face 20 of the grinding wheel 19, is sprayed with water supplied from an apertured conduit 88 (Figs. 3 and 4). Arcuate shaped notches 91 are formed in the upper and lower plates of the guide unit 77 to permit the water to be directed onto the card 21 as it advances to the grinding wheel 19; the water being applied for lubricating and cooling during the grinding operation, and to flush and carry the ground particles off the card 21 and the annular grinding wheel face 20 into the compartment 26. A stream of water for similar purposes is also sprayed through a channel 92 in the cap plate 32 and against the lower surface of the grinding wheel 19 at one side of the guide unit 78 (Fig. 2), within and adjacent that portion of the annular face 20 of the wheel, which engages the card 21, as shown in Fig. 3, the water being carried and directed between the card 21 and the annular face 20 of the grinding wheel 19. Channel 92 is supplied with water from a pipe 93 extending through the post 31, to which is connected a flexible supply hose 94 (Figs. 1 and 2). Formed in the compartment 26 below the brushes 83 and 84 is an apertured conduit 95 for constantly spraying water across the upper surface of the bottom wall of the compartment, which serves to flush and carry the ground particles washed and brushed into the compartment toward and into a drain opening and conduit 98 at the left end of the compartment. For supplying the conduits 88 and 95 with water, flexible supply hose 99 and 100, respectively, are connected thereto (Fig. 4).

As shown in Fig. 3, the annular grinding face 20 of the wheel 19 is ground with a slight bevel, its outer peripheral edge being in the plane of the advancing material and then rising therefrom. This provides an arcuate shaped relatively narrow peripheral line of engagement thereof with the surface of the constantly advancing strip or card 21. In order to facilitate the maintenance of this bevelled grinding wheel face 20, a dressing tool, indicated in general at 101 (Fig. 2), is carried on the vertically adjustable frame 24. The tool 101 comprises a bearing member 102, which is secured to a surface 105 on the frame 24, the surface 105 being ground to extend perpendicular to the bevelled grinding wheel face 20 and is formed with an opening to freely receive a holder 106, which is reciprocably carried in the bearing member 102 for movement parallel to the bevelled grinding

wheel face 20 and keyed at 108 to the member 102 to prevent its rotation. Secured to the holder 106 is a diamond or other suitable tool 109, which is arranged, when the holder is reciprocated to the right (Fig. 2), to engage the bevelled face 20 of the rotating wheel 19 and, in moving parallel thereto, to dress it. A pinion 112, secured to a shaft 113 journalled in the member 102, engaging rack teeth 114 formed on the periphery of the holder 106, upon being rotated clockwise, by a handle 115 fixed to the shaft 113, causes the tool 109 to advance across the rotating annular inclined grinding wheel face 20 to dress it. For each dressing operation of the grinding wheel face 20 when compensation for wear thereon is to be effected, the vertically-adjustable frame 24 is micrometrically raised by rotating the hand wheel 40 an amount sufficient to permit the diamond tool 109 to engage and dress the face 20.

It will be assumed that before the apparatus is set in operation, the guide units 76, 77 and 78 for the particular thickness of strip or card 21 to be ground have been arranged on the frame 24 in proper relation to the sets of feed rollers 50 and 51 and 52 and 53, the backing plate 79, and the bevelled annular face 20 of the grinding wheel 19, the latter being effected in the manner previously described by rotating the hand wheel 40. Also, water is being sprayed from the apertured conduits 88 and 95 and the channel 92. After starting the motor 17 to cause the grinding wheel 19 to be rotated in the direction of the arrow in Fig. 4 and causing the drive (not shown) to the sprocket chain 75 to be set in motion and thus rotating the feed rollers in the direction of the arrows in Fig. 3, a strip or card blank 21 is placed on the apron or lower guide plate extending from the guide unit 76 and against a guide strip 116 by the operator. Upon advancing the blank 21 to the feed rollers 50 and 51, it will be fed thereby and through the guide unit 77 and between the left hand portion of the rotating bevelled annular face 20 of the grinding wheel 19 and the backing plate 79, where it is ground to a predetermined thickness. As the ground blank continues its advance, it enters the inclined guide unit 78, is advanced past the brushes 83 and 84, and is guided to the feed rollers 52 and 53 which, as described hereinbefore, have a slightly greater peripheral speed than the rollers 50 and 51. By providing this peripheral speed differential between the two sets of rollers for maintaining the blank under tension for a great part of the grinding thereof, it has been found that, in grinding the longer strips, a more uniform grinding is effected.

What is claimed is:

1. An apparatus for grinding strip material to a uniform thickness throughout its length and breadth comprising a stationary base over which the material may be passed, an abrasive wheel having a radially extending ring-shaped bevelled abrading surface, the outer peripheral edge of said surface being in the plane of the advancing material and then rising therefrom, means for guiding said material to a point adjacent the outer peripheral edge of said wheel and between said abrading surface and said base so that said abrading surface makes substantially an arcuate line contact at said peripheral edge with the material, and means for flexing and guiding the abraded material from a point adjacent the inner peripheral edge of said abrading surface and 75 away from a diametrically opposite arc of said

abrading surface whereby only a single continuous arc of said abrasive wheel is effective to abrade said material.

2. In an apparatus for grinding advancing strip material to a uniform thickness throughout its length and breadth, a grinding wheel rotatable about an axis arranged perpendicular to the direction of advance of the material at the point of grinding and having an annular bevelled grinding face, the outer peripheral edge of said face being in the plane of the advancing material and then rising therefrom, a backing plate disposed laterally of said axis for supporting the advancing material in predetermined substantially arcuate line contact with the outer peripheral edge of said face, and flexing and guiding means at each side of said backing plate for the material in its advance to and past said backing plate arranged to deflect the material after being ground from the plane of said face.

3. In an apparatus for grinding advancing strip material to a uniform thickness throughout its length and breadth, a grinding wheel rotatable about an axis arranged perpendicular to the direction of advance of the material at the point of grinding and having an annular bevelled grinding face shaped to make substantially an arcuate line contact at its external peripheral edge with the material, the external peripheral edge of said face being in the plane of the advancing material and then rising therefrom, a backing plate disposed laterally of said axis for supporting the advancing strip material in predetermined operative relation with one portion only of said face, and flexing and guiding means adjacent each side of said backing plate and the inner and outer peripheral edges of the grinding wheel for the material in its advance to and past said backing plate arranged to deflect the material after being ground from the plane of said face.

4. In an apparatus for grinding advancing strip material to a uniform thickness throughout its length and breadth, a grinding wheel mounted in a fixed position and rotatable about an axis arranged perpendicular to the direction of advance of the material at the point of grinding and having an annular bevelled grinding face, the external peripheral edge of said face being in the plane of the advancing material and then rising therefrom, a backing plate disposed laterally of said axis for supporting the advancing material in predetermined substantially arcuate line contact with the outer peripheral edge of said face, flexing and guiding means at each side of said backing plate for the material in its advance to and past said backing plate arranged to deflect the material after being ground from the plane of said face, reciprocatory means for supporting said backing plate and said guiding means, and means for actuating said reciprocatory means to micrometrically position the same and thereby said backing plate and said guiding means relative to said face.

5. In an apparatus for grinding advancing strip material to a uniform thickness throughout its length and breadth, a grinding wheel rotatable about an axis arranged perpendicular to the direction of advance of the material at the point of grinding and having an annular bevelled grinding face, the outer peripheral edge of said face being in the plane of the advancing ma-

terial and then rising therefrom, laterally of said axis for supporting the advancing material in predetermined substantially arcuate line contact with an ever-changing portion of the outer peripheral edge of said face, cooperating material advancing means arranged in different levels at opposite sides of said face, one of said advancing means serving to advance the material between said backing plate and the ever-changing portion of said grinding face, flexing and guiding means for the material arranged between said backing plate and the other of said advancing means for deflecting the material from the plane of said face and to said other advancing means, and means for actuating said advancing means.

6. In an apparatus for grinding advancing strip material to a uniform thickness throughout its length and breadth, a grinding wheel rotatable about an axis arranged perpendicular to the direction of advance of the material at the point of grinding and having an annular bevelled grinding face, the outer peripheral edge of said face being in the plane of the advancing material and then rising therefrom, a plate disposed laterally of said axis for supporting the advancing material in predetermined substantially arcuate line contact with an ever-changing portion of the outer peripheral edge of said face, cooperating material advancing sets of rollers arranged in different levels at opposite sides of said face, one set of said advancing rollers serving to advance the material between said backing plate and the ever-changing outer peripheral edge portion of said face, flexing and guiding means for the material arranged between said backing plate and the other set of said advancing rollers for deflecting the material from the plane of said face and to said other set of advancing rollers, said latter advancing set of rollers being slightly larger in diameter than said other set of rollers so that they have a greater peripheral surface speed than said other set of rollers, thus tending to advance the material at a faster rate of speed than that of said other set of advancing rollers whereby the material extending between said sets of rollers and while being ground is subjected to tension, and means for actuating said advancing sets of rollers.

ANTON J. BRUNNER,
AUGUST WENNERBERG.
